UNITED STATES PATENT OFFICE.

ARTHUR JOHN CHARLES BROOKES, OF BRIDGNORTH, ENGLAND.

FORM OF END-MEASURING BAR.

Application filed July 28, 1924. Serial No. 723,761.

To all whom it may concern:

Be it known that I, ARTHUR JOHN CHARLES BROOKES, a subject of the King of Great Britain and Ireland, and residing at

5 Lower Faintree, Bridgnorth, in the county of Salop, England, have invented a certain new and useful Improved Form of End-Measuring Bars, of which the following is a specification.

10 This invention relates to improvements in the form of end measuring bars of high accuracy.

The finished measuring bars may have the measuring faces truly flat and parallel 15 when they are supported in two certain positions; one when the bars are supported in any manner in a truly vertical position and the other when the bars are supported in a horizontal or inclined position in a particular manner upon two rigid supports.

20 Referring to the horizontal supporting position in practical use of the measuring bars, it is necessary to support them upon two (or more) rigid supports, two supports being now commonly employed when the bars have lengths exceeding about 5 inches and when they are of conveniently small diameter it is found that they sag downwards, due to the natural gravity action, on either side of each support. This 25 natural sagging will cause the measuring faces or ends of the bars to be out of parallel with each other in all positions of the two supports relative to the bars, excepting 30 when the two supports are placed symmetrically about the middle of the bars at a distance apart corresponding to 0.5774 of the total length of the bar so supported, it being understood that the bars are of uniform 35 cross-section throughout their length.

40 It should be observed that it has been common practice, when making comparisons in horizontal measuring machines, to support ordinary measuring bars, of uniform cross-section, upon adjustable supports, the distance apart of which is adjusted in accordance with a formula proposed by the late Sir George Airy, about the year A. D. 1857, where the distance apart of the supports corresponds to:

$$l = \frac{L}{(n^2 - l)^{1/2}}$$

where

L =total length of bar of uniform section; 55
 n =number of supports employed;
 l =distance apart of supports.

In the general use of the measuring bars made as described in British specification No. 186,149 of 1922 it is convenient to use 60 them for direct reference of size when supported upon any table or bench, or machine base, the surfaces of which may be uneven and not truly flat, it being the main purpose to use these bars without reference to 65 a measuring machine, and the present invention consists in forming raised collars (hereinafter referred to as "nodal bands") that are portions of the bar raised above the general surface of the bar at two points 70 corresponding to points of support, which, when the bars are in a horizontal or approximately horizontal position, will cause the measuring faces to remain parallel to 75 each other; it then follows that bars having these two nodal bands correctly placed upon them, and with truly parallel end faces, will maintain the end faces parallel to each other when lying upon any surface with which the nodal bands only are in 80 contact.

The nodal bands may be formed integral with the bars or may be added bands. A 85 convenient width of the bands is about $\frac{1}{4}$ -inch, and the band will be effective if raised above the general surface of the bar about $1/20$ -inch.

In the preferred construction according to the invention raised nodal bands upon 90 end measuring bars of uniform cross-section are placed at two points symmetrically disposed about the middle of the bars and at a distance apart equal to 0.5774 of the length of the bars.

The accompanying drawing illustrates one 95 mode of carrying out the invention.

Figure 1 is a front elevation of a circular cross-section measuring bar;

Figure 2 is an end view of same.

In carrying the invention into effect in 100 one convenient manner the main body of the bar, a , is ground reasonably true and approximately cylindrical and with the nodal bands, b , above the general surface. The nodal bands then remain as two small 105 portions of the bar which can be more easily

ground truly cylindrical, of equal diameters and with the common axis normal to the parallel end faces, *c*.

The principal advantage of manufacture contained in these raised nodal bands, is that these two short lengths of the bar are the only portions which it is necessary to make of equal diameters and with a common axis normal to the parallel end measuring faces, thereby greatly facilitating the testing of the accuracy of the finished bars.

Having now described my invention, what I claim as new and desire to secure by Letters Patent is:—

15. 1. An end measuring bar with parallel end faces and nodal bands intermediate of the end faces.

2. An end measuring bar with parallel end faces and two nodal bands intermediate 20 of the end faces and disposed symmetrically about the middle of the bar.

3. An end measuring bar with parallel end faces and two nodal bands intermediate of the end faces and symmetrically disposed about the middle of the bar and at a distance apart such that when the bar is supported on the nodal bands the end faces remain parallel to one another under the bending due to gravity action.

4. An end measuring bar having two nodal 30 bands intermediate of the end faces and symmetrically disposed about the middle of the bar and the centres of which are separated by a distance equal to 0.5774 times the length of the bar. 35

5. An end measuring bar having parallel end faces and two nodal bands integral with said bar and intermediate of the end faces.

In testimony whereof I have signed my name to this specification.

ARTHUR JOHN CHARLES BROOKES.
